UNITED STATES PATENT OFFICE.

CONLEY GAY, OF MIDDLETOWN, NEW YORK.

GAME.

1,338,502.

Specification of Letters Patent. Patented Apr. 27, 1920.

Application filed August 8, 1919. Serial No. 316,111.

To all whom it may concern:

Be it known that I, CONLEY GAY, a citizen of the United States, residing at Middletown, in the county of Middletown and 5 State of New York, have invented new and useful Improvements in Games, of which the following is a specification.

This invention has reference to a game.

The principal object of the invention is 10 to provide a simple inexpensive device whereby young and old may obtain a maximum amount of amusement in playing the game.

The object of the game, which is entitled 15 "Right of way" and which may be played by two or more players, is to move playing pieces, representing railway coaches from a siding to a main line, the player getting all of the playing pieces properly arranged 20 upon a main line winning the game. The game is played with cards as well as with playing pieces, and the object of each player is to prevent the opposing player by blocking 25 the arrangement of the playing pieces on the main line which is accomplished by the denominational value of the cards turned up as well as by a proper manipulation of the playing pieces.

Other objects of the invention will appear 30 as the following specific description is read in connection with the accompanying drawings, which form part of this application, and in which:

Figure 1 is a plan view of the playing 35 board.

Fig. 2 is a sectional view approximately on the line 2—2 of Fig. 1.

Fig. 3 is a perspective view of one of the 40 playing pieces.

Fig. 4 is a plan view of one of the disks indicating the class of trump.

Fig. 5 is a reverse view of the same.

Fig. 6 is a view of one set of cards employed.

45 The playing board may be in the nature of a sheet of card board which is kerfed in the center thereof or otherwise weakened so that the same may be folded to bring its outer faces against each other. The 50 weakened or fold line is reinforced on the rear face of the board as indicated by the numeral 8, the board proper being designated by the numeral 9. The board has inscribed thereon the figure of a Maltese cross, 55 the center of which being in the nature of a square and designating the "home" or space

to be reached by the player. The "home" is indicated by the numeral 10, the angle sides or members of the cross by the numerals 11. The members 11 are imprinted 60 with lines parallel to their outer edges and are provided with transverse lines dividing each of the spaces between the said inner lines, indicated for distinction by the numerals 12, and the outer edges of the members or arms of the cross into six equally 65 divided spaces, each space being differently and consecutively numbered 1 to 6. These inscribed spaces designate the main lines of a railway system. The side lines of the system are arranged between the arms of the cross, the said side lines being provided by inscribing the board with spaced parallel 70 lines and transverse dividing lines which divide the same into six equal spaces 13, which are numbered consecutively from 1 to 6 and which are designated by the numerals 14. It will be noted that the sidings are arranged radially of the board, and between 75 the ends of the side lines and the ends of the arms of the Maltese cross are substantially rectangular impressions indicated by the numerals 15, and numbered six and each indicating a tower. Between the inner lines 12 of the arms of the Maltese cross are circular impressions 16, one designated by the character A, and the other by the character B, the other by the character C and the last by the character D. In these circular 80 impressions are imprinted the word "class" 85 and if desired the word "trump."

A deck of cards are employed, and the faces of these cards have imprinted thereon characters representing an operator, which has the highest playing value, that of six 90 points and on the suits of these cards are imprinted the class to which they belong, either A, B, C or D. Other suits of cards designate the engineer, which has the next highest playing value, that of five points, 95 the same having the class also imprinted thereon, which is true of the remaining cards in the suits of the deck. The next highest valued cards are those of the fireman which are entitled to four points. 100 Then comes the suits of cards indicating the detective, the train robber and the baggage master, each of which having a value of three points. After this is a suit representing the brakeman which have a playing 105 value of two points and the final suit of cards representing the conductors which 110

have a playing value of 1 point. The cards are broadly indicated by the numerals 16.

In addition to the cards, two disks are employed. These disks are differently colored from the indicia on the board and from the playing pieces which will hereinafter be referred to. On one of the faces of each of the disks, which are represented by the numerals 17 is imprinted the character A, 10 and also the words "class" and "trump". On the reverse side of this disk is imprinted the letter B and also the words "class" and "trump". On the second disk there is centrally imprinted the character C and the 15 words "class" and "trump", and on the reverse side of this disk is imprinted the character D and the words "class" and "trump".

The playing pieces are in the nature of 20 blocks, a desired number being employed and the blocks used by each of the players are six and the same are consecutively numbered from one to six. The blocks are broadly indicated by the numerals 19. The 25 blocks or playing pieces, the disks and the cards when the board is not in use and folded, are designed to be arranged in a suitable box or receptacle which, if desired, may be attached to the board.

30 The playing pieces are placed on the corresponding numbers in the sidings. The cards are dealt, five cards being given to each player and one is turned up from the bottom to indicate the trump. If class A, 35 should be the trump card, the player having class B should lead. Suppose the player of class B plays the baggage master, then the player in class C plays the train robber and the player of class D plays the detective. 40 The detective takes in the playing pieces of the players of class A, B and C, which

gives class D the first block, for instance, the block 3 from the siding, so that the playing piece 3 is placed on the main line. A full hand, if rightly played, will give 45 the holder all of the tricks and will give the player of such a hand the right of way at any time throughout the game. Each player must play from right to left and make the full three runs before the 50 game is out. In playing the card 6 will give the player the block 6 or tower. This gives the player the right to move on second space in his class or on his main line, and block 6 must be kept in the tower for at least 55 three moves, but all of the blocks can be arranged upon the main line and the game won by one of the players.

Having thus described the invention, what is claimed as new, is:—

60 A game designed to be played by playing pieces, disks representing classes and cards having various playing values, comprising a board having imprinted thereon a figure of a Maltese cross, the arms of which being 65 divided into spaces at the edges thereof and said spaces differently numbered and representing the main lines of a railway system, the center of the cross representing "home" and each of the crosses having imprinted 70 therein a disk with a character similar to that of the first mentioned disks, said board having radial spaced lines provided with transverse divisions between the arms of the cross, the said divisions being numbered 75 from one to six consecutively and representing a siding, and rectangular impressions between the siding and the arms of the cross having characters imprinted thereon and representing towers.

80 In testimony whereof I affix my signature.

CONLEY GAY.
